CHARLES FRANKLIN MOBLEY, OF BIRMINGHAM, ALABAMA.

METALLIC RAILROAD-TIE.

1,056,201.

Specification of Letters Patent.

Patented Mar. 18, 1913.

Application filed June 24, 1912. Serial No. 705,659.

To all whom it may concern:

Be it known that I, CHARLES F. MOBLEY, a citizen of the United States of America, residing at Birmingham, in the county of 5 Jefferson and State of Alabama, have invented certain new and useful Improvements in Metallic Railroad-Ties, of which the following is a specification.

My invention relates to an improvement 10 in metallic railroad ties having for its principal object to perfect the means for fastening the rails to a metallic tie of the general construction described and claimed in my pending application, Serial No. 659,001, 15 filed on the 7th day of November, 1911.

One object of my invention is to form the rail supporting member of the tie of sheet metal in which depressed seats are provided having integral overhanging shoulders be- 20 tween which the rails and their fastening means are received and locked in engagement.

Another object of my invention is to increase the strength and resiliency of the rail 25 seats by bending their corner edges on a curve which overhangs the side walls of the tie forming a bead along each side edge be- 30 tween the overhanging seat shoulders.

A still further object is to improve the 35 design and construction of wedge locking means which co-act with the overhanging shoulders of the tie and interlock with the base of the rail so as to hold it firmly and rigidly in position and yet permit it to be readily detached from the tie.

A further object is to provide one shoulder of each seat with an inner wedge face 40 for engagement with a locking wedge key, and to so arrange the wedge shoulders on each tie, that by reversing successive ties the wedge keys in engagement with each rail 45 will be staggered and the alternate keys for one rail that are removable in one direction, will be on the opposite side of said rail from the interposed alternate keys which are removable in the opposite direction. This prevents any loose part of a train being able to drag and strike the keys of successive ties with a tendency to dislodge them, regardless

of the direction of movement of the train, 50 for the same train part could not drag and strike the keys on both sides of the same rail and only the keys of alternate ties will be on the same side of a given rail.

My invention further comprises the de- 55 tails of construction and arrangement of parts which, in their preferred embodiment, are illustrated in the accompanying drawings, in which:

Figure 1 is a side elevation of my im- 60 proved tie broken away at one end to show the rail and locking means in vertical cross section. Fig. 2 is a plan view of one end of Fig. 1, showing the top plate broken away to illustrate its joint with the upturned end 65 of the base plate. Fig. 3 is a vertical sec- 70 tional view taken along the line $x-x$ of Fig. 1. Fig. 4 is an enlarged perspective detail view of one end of the tie taken on a cross section through the seat and showing the flanges on the base before they are bent to interlock with the flanges of the top section 75 of the tie. Fig. 5 is a detail perspective view of one of the fillets forming part of the rail locking devices.

Similar reference numerals refer to simi- 75 lar parts throughout the drawings.

In its preferred construction the tie is formed by a metallic base 1 having longitudi- 80 nal and parallel inner lugs 2 and having outer flanges 3 which are spaced from the lugs 2 to form seats for the reception of the bottom flanges 4 of the hollow metal body 5 which forms the top portion of the tie. The ends 6 of the base are turned up at right 85 angles and the body portion 5 has end flanges 7 which are engaged by the upturned por- 90 tions of the lugs 2 and flanges 3 on the base. The top also has its ends 8 bent down and adapted to fit over the ends 6 of the base. By this arrangement the top and bottom portions of the tie are firmly locked together and yet their connection is such that the tie, as a whole, has sufficient resiliency or give to best adapt it to the service 95 required.

The top portion 5 is preferably formed from sheet metal which is bent in inverted

U-shape in cross section and is shaped to have two depressed rail seats 9 which are overhung at each end by integral raised shoulders 10 and 11. In forming the seat 5 and shoulders, I prefer to press the metal so as to bulge out the side corners of the seat on an overhanging curve forming the bead 12 along each side edge of the seat. These beads extend only the length of the seats 9 10 and provide a wider, stronger and more resilient support for the rail than would any other part of the tie.

As a part of the rail fastening means, I 15 provide a fillet 13 (see Fig. 5) which has its ends 14 bent over so as to overhang and engage the side walls of a seat 9. The fillet has an inclined overhanging shoulder 15, the upper surface of which is shaped to fit under and be closely engaged by the overhanging seat shoulder 10. I also provide for each rail fastening, a locking key 16 which has a lip 17 overhanging an extension base 18 which rests on the seat 9 and supports the rail. The outer side edge of the 20 key is tapered and its narrow end is provided with a tongue 19 adapted to be bent outwardly against the end of a shoulder 11 to lock the key in adjusted position. It will be noted that the cross sectional contour of 25 the key is such as to cause it to fit snugly under the overhanging shoulder 11. The base of the rail 20, when in position, will be supported partly by the fillet 13 and the base 18 of the key and it will be gripped by 30 the lips 15 and 17 so that when the key is driven home the rail will be held firmly in 35 position.

In practice, the fillets 13 are inserted in 40 position under the shoulders 10 which are spaced so that when the rails 20 are locked in engagement therewith by the keys 16, they will be spaced the desired track gage. The keys 16 which have their base portions 45 18 slipped under the rails and are then driven in their wedge faces engaging the wedge faces of shoulders 11 and gradually forcing the keys to the right until the rails are gripped between the keys and fillets and locked in position under the shoulders 15 50 and 17. The tongue 19 on the key is bent out and the rail fastening parts are locked in position. If it is desired to vary the gage of the track, this may be done by varying the thickness, lengthwise of the 55 rail, of the key 16 or of the fillet 13. For instance, the right hand fillet in Fig. 1 could be made thinner and the left hand fillet 13 made thicker, which would result in spreading the rails and widening the 60 track gage. If it is desired to narrow the gage the reverse arrangement of the fillets would be used. The wedging action of the key or rail chair against the shoulder 11 enables the key to be driven in until it

forms a tight, non-rattling, joint which can- 65 not work loose without the breaking of the tongue 19. The overhanging lips 14 prevent the fillet working loose after the rail is locked in position. To remove the rails it is only necessary to bend the tongue 19 70 back into initial position and drive the wedge rail chairs or keys 16 out.

I prefer to have the wedge faces of the shoulders 11 of each tie similarly disposed so that the keys will have to be driven in 75 from the same side of the tie and I also prefer to dispose one shoulder 11 on the outside of one rail and the other shoulder 11 on the inside of the other rail. My ob- 80 ject in this is to reverse the position of successive ties so that the keys 16 on one tie will drive from the front and be on the left hand side of both rails, while the keys on the next succeeding tie will drive from the rear and will be on the right hand side 85 of both rails and so on throughout the track. This arrangement brings the keys of alternate ties only into alinement on the same side of a rail which they fasten, hence, no dragging part of the rolling stock can strike 90 and injure or tend to loosen keys of successive ties but it could only strike keys of alternate ties, it being practically impossible for the same dragging part to strike the keys on both sides of the same rail and 95 only by doing that could the rail fastenings of successive ties be affected.

I have shown the tie as a hollow metal body but if desired it may be filled with any suitable material of a yielding nature, such 100 as wood fiber and like material.

Having thus described my invention, what I claim as new and desire to secure by Letters Patent, is:—

1. A metallic railroad tie formed of a 105 shaped metal plate provided on its top surface with two depressed rail seats and integral shoulders overhanging the ends of each seat and standing above the rail base when seated thereon, a rail chair adapted to be 110 inserted in each seat and having a lateral wedge face adapted to engage under one of said shoulders, and having a lip overhanging the adjacent side of a rail's base, means adapted to engage under the other of said shoulders and over the rail base to hold it in said seat, said means being adapted to bring the rail base closer to its retaining shoulder than to the other shoulder, and means to lock the rail chair in position. 115

2. A metallic railroad tie provided with two rail seats and shoulders overhanging the ends of each seat, a two-part rail chair adapted to be inserted in each seat and to engage under the shoulders thereof and below the rail when seated, one part comprising a narrow fillet which sets close in under one shoulder and has a lip overhanging the 120 125

adjacent side of the rail base, the other part being an adjustable wedge-shaped filler block which also has a lip overhanging the opposite side of the rail base, and means 5 to hold said wedge and fillet in the seat, substantially as described.

3. A metallic railroad tie having its rail supporting body formed of a metal plate shaped to form two rail seats interposed between 10 pairs of integral raised overhanging shoulders, the correspondingly disposed shoulders at one side of each seat having a face opposed to the rail and disposed at an acute angle to the longitudinal center line 15 of the rail, the other shoulders having faces similarly disposed relatively to said center line of the rail, filler blocks which engage the latter faces, and adjustable wedge keys which engage the former faces.

20 4. A metallic railroad tie having its rail supporting body formed of shaped sheet metal which is depressed to form two rail seats, and raised to form two overhanging end shoulders for each seat, the side edges 25 of each seat being formed with an overhanging curved reinforcing bead, substantially as described.

5. A metallic railroad tie having depressed rail seats each overhung by a pair of shoulders, a two-part chair adapted to engage under 30 the shoulders and having portions adapted to overhang the rail base and portions adapted to support the rail base, one part of the chair being made wider than the 35 other part to adjust the rail closer to one shoulder than the other, and the part of each chair which engages the shoulder farthest from the rail having its portion underlying the rail extending more than half way 40 under the same, substantially as described.

6. A metallic railroad tie having a rail supporting integral body portion formed of sheet metal shaped to form two pairs of spaced overhanging shoulders, a rail adapted to be received between each pair of shoulders, the corresponding shoulders of each pair being similarly disposed to make the tie reversible, and one pair having parallel faces inclined relatively to the side line of 50 the rails, and fastening means for said rail comprising a fillet which is overhung by the corresponding shoulder of each pair and grips one side of the rail base and a wedge key which engages the correspondingly inclined 55 faces of said shoulder and grips the other side of the rail base, and means to fasten said key in operating position.

7. A metallic railroad tie having two pairs of overhanging shoulders, the underface 60 of the overhanging portions slanting upwardly toward their ends, a fillet having overhanging ends which straddle the tie and which is tapered to fit under one of said shoulders, a wedge key tapered to fit under

the other shoulder and having a tongue at 65 its small end adapted to be bent to lock the key in position, said key and fillet each being recessed to receive between them and support the base of a rail, substantially as described. 70

8. In a metallic railroad tie, a rail supporting body portion which is formed of shaped sheet metal, said body portion comprising two spaced rail seats and integral overhanging shoulders at each end of said 75 seats, the vertical inner wall of corresponding shoulders being disposed obliquely across the narrow face of the tie, a rail chair having a wedge face adapted to engage said inclined inner wall of the shoulders, fillets 80 adapted to engage under the other shoulders, said fillets and chairs having portions to support and overlap the base of the rail, a portion of the tie under said chairs having its corners struck on a curve which overhangs the seats of the tie, and means to fasten the chairs in operating position, substantially as described. 85

9. A metallic tie, comprising a base which is longitudinally flanged and has end flanges, 90 of a bent metal body, the ends of which abut against said end flanges, and which has out-turned bottom flanges, said longitudinal base flanges being adapted to be bent to overlap said body flanges and interlock the parts 95 free of rigid connections.

10. In a metallic tie, a base having upturned ends, a bent metal body portion adapted to be received between said ends and held thereby against longitudinal movement on the base, out-turned bottom flanges on the side walls of said body, and pairs of spaced longitudinal flanges on the base which receive between each pair a bottom flanged portion of the body and one or more of 105 which are bent over to engage said bottom flanges and interlock the body and base free of rigid connections. 100

11. In a metallic tie, a base having upturned ends and longitudinal raised flanges 110 disposed along the bottom and ends, and a top formed of bent metal and having flanges which are adapted to interlock with said flanges on the base and serve as the means for connecting the tie sections together. 115

12. A metallic tie, comprising a base plate provided with upturned ends, raised flanges disposed longitudinally along each side of the base and its ends, a body portion comprising a top and sides bent downwardly 120 and provided with an out-turned bottom flange, similar flanges on the ends of said side walls, said base flanges being adapted to be bent over and engage the flanges of the top and interlock the parts, substantially 125 as described.

13. A metallic tie comprising a wide metal base having a pair of longitudinal vertical

flanges disposed adjacent to each side and having its ends turned up, similar disposed pairs of flanges on the inside face of each upturned end, a body portion of an inverted 5 U-shape having the bottom and end edges of its vertical sides provided with out-turned flanges which are adapted to be received between the said pairs of flanges in the base, the corresponding flange of each pair being

adapted to be bent over and lock the body 10 flange to the base, substantially as described.

In testimony whereof I affix my signature in presence of two witnesses.
